UNITED STATES PATENT OFFICE.

MELVIN D. KILMER, OF CLEVELAND, OHIO.

WINDOW-SASH FASTENER.

1,164,724.

Specification of Letters Patent. Patented Dec. 21, 1915.

Application filed March 18, 1915. Serial No. 15,249.

To all whom it may concern:

Be it known that I, MELVIN D. KILMER, a citizen of the United States, residing at Cleveland, in the county of Cuyahoga and State of Ohio, have invented certain new and useful Improvements in Window-Sash Fasteners, of which the following is a specification.

My invention relates to improvements in window sash fasteners, and more particularly to that class or type known as "venting sash fasteners" that is to say,—a fastener which is adapted to hold or secure the upper or lower sash of a window, or both the upper and lower sashes when in a partially open position for the purposes of ventilation.

The primary object of my invention is to provide a generally improved sash fastener of this class, which will be exceedingly simple of construction, cheap of manufacture, efficient in use, and which may be readily and quickly attached to and detached from any ordinary window sash without the use of screws, nails, or other attaching elements, and also without the use of any tools in the application of the improved fastener.

A further object is the provision of a lock or fastener of this class which may be carried in the pocket or handbag of a traveler for ready application to both the upper and lower sashes of an ordinary window for holding or securing such sash as against the further opening movement when either in a fully closed or partially closed position.

A still further object is the provision of a fastener of this class which will effectively coöperate with and lock the upper and lower sashes in any adjusted position without in any way marring or injuring the same while in use, as well as one which will in no way interfere with the free movements of either or both sash members to closed position without first moving or readjusting the lock or fastener.

A still further object is the provision of a fastener of this class which will not only be fully automatic in operation, but which may be readily held or secured in released or inoperative position as in washing the window sash, and in other cases where it is desired that the lock shall not be operative or automatic in its operation.

With the above mentioned and other ends in view, the invention consists in the novel construction, arrangement, and combination

of parts, hereinafter described, illustrated in some of its embodiments in the accompanying drawings, and particularly pointed out in the appended claims.

Referring to the drawings, forming a part of this specification, Figure 1, is a vertical sectional view of the improved ventilating sash fastener in its operative position applied to the upper and lower right hand corners of the lower and upper sash members, respectively, of a window, the sash members of the window being in a partially open position for the purposes of ventilation. Fig. 2, a front elevation of the same. Fig. 3, a view similar to Fig. 1, showing a slightly modified form held in unlocked or inoperative position for washing the sash, or the like, with a slightly modified form of mounting or method of attachment. Fig. 4, a front elevation of the same.

Similar numerals of reference designate like parts throughout all the figures of the drawings.

The improved sash fastener comprises an attaching or base plate 1, carrying an upwardly projecting bearing housing 2, open at its front and rear sides as shown, to receive and contain a spring resisted pivotally mounted cam 3, which latter projects from the front and rear sides of the housing and is mounted on a bearing pin or member 4.

The front or projecting portion of the cam 3, is provided with a curved segmental recess 3^a, and a dove-tailed recess 3^b, to receive and contain a removably mounted similarly shaped sash engaging resilient member 3^c, adapted to ride upon and engage with the face side of the upper sash, and at the same time prevent any marring or defacement of such portion of such upper sash.

The rearwardly projecting portion of the cam comprises an offset operating handle 3^d, by means of which the cam 3, may be temporarily held out of engagement with the upper sash.

As a means of holding the cam 3, into operative engagement with the upper sash so as to lock or fasten the sash members in any position in which they may be adjusted for ventilation, a coiled spring 5, is interposed between the attaching or base plate 1, and the handle 3^d, the ends of said spring being held in position by the stud members 5^a, in an obvious manner.

As a means of holding the cam 3, in an inoperative position or out of engagement

with the upper sash as against the resistance of the expansion spring 5, to prevent the automatic operation of the cam member as in washing windows, and the like, the rearwardly projecting or handle portion 3^a, of the cam is provided with a recess or opening 3^e, to receive an intercepting element 6, such as a nail, hair pin, or the like, such intercepting element passing through the recess 10 or opening 3^e, and at the rear of the housing to hold the cam in an inoperative position as indicated most clearly in Figs. 3 and 4 of the drawings. It will be observed that in the form or embodiment shown in Figs. 3 15 and 4 of the drawings the attaching or base plate 1, is secured to the top of the lower sash by means of attaching screws 7, while in the form shown in Figs. 1 and 2, a special form of attaching or clamping plate to 20 be now described is employed.

As a means of more readily and quickly attaching the improved fastener to or detaching the same from any ordinary window sash without the use of screws, nails, 25 or other attaching elements, the attaching or base plate 1, is preferably provided with a depending anchor portion 1^a, the latter being adapted to be interposed between the rear upper portion of the lower sash 8, and 30 the adjacent lower front or face side of the upper sash 9, it being apparent that the parts 1, and 1^a, are formed at such an angle as to conform to the form or contour of the upper portion of the lower sash and that the 35 depending anchor portion 1^a, is adapted to prevent any longitudinal movement of the attaching or base plate 1, when the locking or latching cam 3, is brought into co-operative engagement with the upper sash 9. As 40 a means of detachably securing the attaching or base plate 1, to the upper portion of the lower sash the front portion of the base plate 1, is provided with a depending clamp member 10, provided with a threaded portion adapted to receive and contain a threaded clamping bolt 11, said clamping member 11, being provided with a winged or thumb head 11^a, the opposite end of the clamping bolt being provided with a loosely mounted 45 clamping head 12. By means of this clamping device it will be seen that the attaching or base plate 1, may be readily attached to the upper portion of the lower

sash of any ordinary window and at the same time may be readily detached if desired. 55

From the foregoing description, taken in connection with the accompanying drawings, the operation and advantages of my invention will be readily understood. 60

Having thus described some of the embodiments of my invention, what I claim and desire to secure by Letters Patent, is,—

1. A sash fastener, comprising an attaching plate carrying a bearing housing, and a pivotally mounted cam in said housing and projecting from the front and rear sides thereof, the front side of said cam being provided with a curved segmental recess and the rear side with an offset operating handle having an opening adapted to be moved to a plane at the rear of said bearing housing, a coiled spring interposed between the base of said housing and said offset operating handle, an intercepting element adapted 75 to be inserted in said opening and to engage the rear of said housing whereby said cam is held in an inoperative position, and a curved resilient upper sash engaging member removably mounted in said segmental 80 recess at the front side of said cam.

2. A sash fastener, comprising a base plate carrying an overhanging housing open at its front and rear sides said base plate being also provided with a projecting spring 85 receiving stud, a cam pivoted in said housing and projecting from the front and rear sides thereof, the rearwardly projecting portion of said cam being offset to form a handle provided with an opening to receive an intercepting element and a depending spring receiving stud above said stud of said base plate, a coiled expansion spring taking over said spring receiving studs and interposed between said base plate and said handle, and 90 an intercepting element in said opening of said handle passing at the rear of said housing to hold said cam in an inoperative position. 95

In testimony whereof I have affixed my 100 signature in presence of two witnesses.

MELVIN D. KILMER.
